(57) **CLAIM**

The ornamental design for a pizza cutter, as shown and described.

DESCRIPTION

FIG. 1 is a front perspective view of a pizza cutter showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is the top plan view thereof; and,

FIG. 7 is the bottom plan view thereof.

The broken lines depict portions of the pizza cutter that form no part of the claimed design.
